UNITED STATES PATENT OFFICE.

FREDERICK G. WILCOTT, OF SAN QUENTIN, CALIFORNIA.

BOILER-TUBE CONSTRUCTION.

Application filed July 7, 1925, Serial No. 41,955.

My invention relates to boiler tubes and has particular reference to boiler tube construction for fire tube boilers, and to a lesser degree to the tubes of water tube 5 boilers.

Present tubes for steam boilers are of uniform thickness throughout, the fire passing therethrough impinges on the walls of the tube and with greater impingement on 10 the top wall. This unequal heating of the top and bottom wall, sets up unequal stresses in the tube which eventually may equalize, but it is well known that tubes and boiler heads fracture owing to over-stressed areas 15 beyond the elastic limit of the metal. Also fire tubes are prone to burn out along the top area, and official inspection often requires that defective tubes be removed and replaced by new ones.

20 An important object of my invention is to overcome the above deficiencies by the provision of a liner to be positioned in the tubes and of a design to correct the above inequalities, increase the life of the tubes 25 and likewise the boiler, and reduce the danger of the boiler fracturing at the tubes and heads to a minimum.

Another object is to consider the great 30 number of boilers in use today and so manufacture my liner that the same can be applied thereto, and that liners can be carried in stock to meet the standard sizes of boiler tubes.

Another object is to meet the problem of 35 future boilers, that is, before or after the boiler is built my invention can be applied to the tubes thereof. Also, for future tubes my liner may be incorporated with the tube in its manufacture as a homogeneous unit, 40 but according to the present day process of manufacturing tubes I would conclude that it appears uneconomical to do so at this time.

With the above and other objects in view I 45 will exemplify one form of my invention by the illustration shown in the accompanying drawing in which:—

Figure 1 is a perspective view of the invention per se for existing boilers.

50 Figure 2 is a transverse cross-section of a standard boiler tube with a liner therein in normal position; and

55 Figure 3 is a longitudinal vertical section through a portion of a horizontal fire tube steam boiler; a portion of one of the tubes is shown in full.

Adverting to the figures of the drawing I will now describe the invention in detail: The numeral 4 indicates the liner of my tube construction and throughout the figures 60 it is shown crescent-shaped in transverse cross-section, however, other segmental shapes are to be considered within the sphere of my improvement and as per the scope of the claims following this specification. 65

5 is the ordinary boiler tube of commerce, and in Figure 2, D is the horizontal diameter thereof. The edges 6 of the liner approximate this diameter and preferably terminate below it, in order to insure a close 70 contact of the liner which the major part of the inside surface of the tube, otherwise the liner may separate and drop down from the inside top of the tube unless welded thereto and which I consider inadvisable. In Figure 1, I show the thin edges 6 depending or flared from the true radius, that is, the outer surface is tangent to the circumference of the liner at the diameter D' thereof. The purpose of the flared edges is that when the 80 liner is pressed, driven or otherwise positioned in the tube, the said thin edges will give and bend inwardly and thus effect a tight hold or union with the tube, the curvature of the tube at the edges functioning to 85 thrust the liner upward to contact the tube.

In Figure 3 only two tubes of a series are shown in combination with a boiler, that number being thought sufficient to show the relation of my improvement with the boiler. 90 7 and 8 represent the respective boiler heads, and the tubes 5 are shown in a conventional engagement therewith as at 9. The liners 4 are of a length substantially that of the boiler but less than that of the tube for two 95 reasons, namely: To allow the tube to be expanded or flanged to position in the head in the usual way, and to allow a shouldered recess 10 so that any tool may be supported in the recess to effect the driving of the liner 100 out of the tube if desired, as when burned out or worn for example.

It is obvious that when the thick crown of my tube structure becomes heated, it will 105 retain its heat for some time, thus tending to maintain the steam at an even temperature and pressure, and when the fires are low or banked the pressure and temperature of the steam will be retained longer, due to the slow liberation of heat from the improved tube structure.

From the foregoing description taken in

connection with the accompanying drawing, the advantages of the construction and method of operation will be readily understood by those skilled in the art to which the invention appertains, and while I have described the principle of operation, together with the device which I now consider to be the best embodiment thereof, I desire to have it understood that the device shown is merely illustrative and that such changes may be made, when desired, as fall within the scope of the appended claims.

Having thus described my invention, what I claim as new and desire to secure by Letters Patent of the United States is the following:—

1. In a boiler tube construction, a liner comprising a body segmental in cross-section and having thin, flared edges adapted to hold the liner tightly in contact with the inner wall of the tube.
2. In a boiler tube construction, a crescent-shaped liner comprising a body of size and length adapted to substantially engage the major surface of a boiler tube, said liner having thin, flaring edges adapted to hold the liner tightly in contact with the inner wall of the tube.
3. In a boiler tube construction, a liner

comprising a body substantially segmental in transverse cross-section having an outside radius equal to that of the inside of the tube and an outside circumference greater than one-half of the inside circumference of the tube, the body being relatively thick at its midsection and thin at its edges, and the edges being adapted to hold the liner tightly in contact with the inner wall of the tube.

4. In a boiler tube construction, a liner consisting of a crescent-shaped body relatively thick at its transverse midsection and thin at its edges, the edges being flared outwardly a little from the true outside radius of the body and extending past the diameter of the tube to effect a tight holding of the liner in the tube.

5. In combination with a boiler and the tubes thereof, liners adapted to be driven into the respective tubes, each liner being of segmental shape in cross-section and of a length substantially that of the boiler, and each liner having thin, flaring edges adapted to hold the liner tightly in contact with the inner wall of the respective tube.

In testimony whereof I affix my signature.

FREDERICK G. WILCOTT.
